UNITED STATES PATENT OFFICE.

GEORGE P. KLINE, OF MOLINE, ILLINOIS.

ATTACHMENT FOR MICROMETER-CALIPERS.

1,074,552.

Specification of Letters Patent. Patented Sept. 30, 1913.

Application filed April 22, 1912, Serial No. 692,257. Renewed August 19, 1913. Serial No. 785,593.

To all whom it may concern:

Be it known that I, GEORGE P. KLINE, of Moline, in the county of Rock Island and State of Illinois, have invented certain new and useful Improvements in Attachments for Micrometer-Calipers; and I do hereby declare the following to be a full, clear, and exact description of the invention, such as will enable others skilled in the art to 10 which it appertains to make and use the same.

The primary object of my invention is to provide an improved, simple and highly efficient centering support for measuring instruments, particularly micrometer calipers, which will be self-adjustable and provide a proper seat for a threaded or grooved body and insure accurate measurement. And a further object is to provide a centering support which will be applicable to micrometers now in general use without material alteration.

In the accompanying drawings, Figure 1 is an elevation of a micrometer caliper with 25 my support applied thereto. Fig. 2 is a similar view at right angles to Fig. 1. Fig. 3 is a sectional view of the support. Fig. 4 is a view in perspective.

Referring to the drawings, 1 designates a 30 micrometer of ordinary form having the usual abutment point 2 and an arm 3, within a bore 4 of which is fitted a stud 5 of a holder 6. The latter has a longitudinal groove 7, which is shown as being flared or 35 of dove-tailed formation in cross-section to receive two correspondingly formed triangularly-shaped supports 8 and 9. Of course the groove and the bases of the supports may have any corresponding formation. The outer projecting ends of these 40 supports are beveled and designed to fit within grooves of the threaded body to be measured. The supports form a rest for such body, and by engagement with the threads thereof adjust themselves to the 45 pitch of the latter, insuring a careful adjustment of the work so that an accurate measurement may be obtained. To prevent disengagement of the supports from the holder 50 at the ends thereof I provide stop pins 10. There is sufficient play of the supports between the pins to permit them to readily adjust themselves to grooves of different pitch.

55 The advantages of my invention will

be apparent. It will be seen that a device constructed in accordance therewith may be readily substituted for the means now generally in use without the necessity of altering the construction of the micrometer. 60

In practice the supports are caused to engage the thread, and they are usually separated by one convolution thereof, the point 2 being substantially midway between the two supports. 65

I claim as my invention:

1. In a micrometer-caliper, a detachable base and two oppositely disposed thread-engaging supports both of which are slidably mounted on said base so as to be free to be moved in opposite directions by the 70 thread of the bolt being calipered.

2. In a micrometer-caliper, a detachable base having a groove extending longitudinally thereof, and two oppositely disposed 75 thread-engaging supports both of which are slidable in said groove so as to be free to be moved in opposite directions by the thread of the bolt being calipered.

3. In a micrometer-caliper, a detachable 80 base having a groove, means for securing said base to the caliper, and oppositely movable thread-engaging supports in said base, said supports being capable of said adjustment by engaging the threads of the 85 work to be calipered.

4. In a micrometer caliper having an arm, a detachable base having a flared groove, means for securing said base to said arm, longitudinally adjustable thread-engaging 90 supports mounted on said base and flared at their lower ends to fit in said groove, and stops on said base for limiting the movements of said support.

5. In a micrometer-caliper having an arm, 95 a detachable base having a flared groove, means for securing said base to said arm, longitudinally adjustable supports mounted on said base and flared at their lower ends to fit in said groove, each support being of 100 triangular formation, and stops on said base for limiting the movements of said supports.

In testimony whereof, I have signed this specification in the presence of two subscribing witnesses.

GEORGE P. KLINE.
